United States Patent Office

Des. 222,160
Patented Oct. 5, 1971

222,160

MODEL RACING CAR

Anthony Cyril Rudd, Norwich, England, assignor to
Rubery, Owen & Company Limited, Darlaston,
Wednesbury, England

Filed Aug. 7, 1970, Ser. No. 24,363

Claims priority, application Great Britain Feb. 10, 1970

Term of patent 7 years

Int. Cl. D21—02

U.S. Cl. D34—15

Des. 222,160

PAGE 3

FIG. 1 is a top perspective view of a model racing car showing my new design; and

FIG. 2 is a front perspective view of FIG. 1; and

FIG. 3 is a rear perspective view of FIG. 1; and

FIG. 4 is a left side perspective view of FIG. 2, the right side being substantially a mirror-image thereof.

I claim:

The ornamental design for a model racing car, as shown and described.
